UNITED STATES PATENT OFFICE.

LEROY S. BUFFINGTON, OF MINNEAPOLIS, MINNESOTA, ASSIGNOR TO THE BUFFINGTON LIGHT COMPANY, OF NEW JERSEY.

ACETYLENE-GAS-GENERATING LAMP.

SPECIFICATION forming part of Letters Patent No. 621,217, dated March 14, 1899.

Application filed January 13, 1897. Serial No. 619,063. (No model.)

To all whom it may concern:

Be it known that I, LEROY S. BUFFINGTON, a citizen of the United States, residing at Minneapolis, in the county of Hennepin and State 5 of Minnesota, have invented certain new and useful Improvements in Acetylene-Gas Lamps for Bicycles; and I do hereby declare the following to be a full, clear, and exact description of the invention, such as will enable others skilled in the art to which it appertains to 10 make and use the same.

My present invention has for its especial object to provide an improved acetylene-gas lamp for bicycles, but involves certain features of construction which are adapted for 15 general use on other forms of acetylene-gas lamps or gas-generating apparatus of this general nature.

To the ends above noted my invention consists of the novel devices and combinations of 20 devices hereinafter described, and defined in the claims.

The preferred form of my present invention, shown as especially designed as a bicycle-lamp 25 and shown as applied in working position on a bicycle, is illustrated in the accompanying drawings, wherein like letters refer to like parts throughout the several views.

Figure 1 is a view in side elevation showing 30 a portion of a safety-bicycle with my improved bicycle-lamp applied in working position thereto. Fig. 2 is a similar view to Fig. 1, but illustrating a different manner of mounting the lamp on the bicycle-frame. Fig. 3 is 35 a vertical section taken substantially through the center of that portion of the lamp which I term the "generator." Fig. 4 is a horizontal section through the generator, taken on the line X⁴ X⁴ of Fig. 3, looking upward. Fig. 5 is 40 a perspective view of the sponge-holder or holder for the absorbent material removed from the generator; and Fig. 6 is a detail view, in vertical section, illustrating a modified form of my improved elastic pressure-compensating device or equalizer.

Of the parts of the bicycle *a* indicates the steering-head; *a'*, the frame braces or rods; *a²*, the seat; *a³*, the front fork; *a⁴*, the handle-bars, and *a⁵* a clamping-nut working on the 45 upper end of the steering-head.

In the preferred form of my lamp I have

illustrated the same as formed in two sections, one of which I will term the "bull's-eye," and the other the "generator." This bull's-eye may be of the ordinary form, as indicated at 55 *b*, except that it should be provided with a small gas-burner *b'*. The bull's-eye is supported by means of a bracket *b²*, one end of which is clamped to the upper end of the steering-head *a* by means of the nut *a⁵*. The 60 outer end of the bracket *b²* is formed on the line of the arc of a circle and is secured to the back of the bull's-eye by means of a thumb-screw *b³*, working through a suitable passage in said bracket and screw-threaded into the 65 back of said bull's-eye. In virtue of the curved form of the supporting end of the bracket *b²* the lamp may be given any desired pitch or inclination simply by raising or lowering the same. 70

The chief novelty of my invention is found in the generator. Of the parts of this generator *c* indicates the case of the generator, as shown, in the form of a cylinder, provided with an upper end head *c'* and a lower end 75 head *c²*. The upper head *c'* is shown as provided with a central opening *c³*, adapted to be partially closed in a manner hereinafter described, and the lower head *c²* is provided with a central opening formed by an internally-screw-threaded nipple *c⁴*, which is provided to be closed by means of a screw-threaded cap-nut *c⁵*. The cylinder *c* is divided into an upper chamber *c⁶* and a lower chamber *c⁷* by means of a horizontal dividing-partition *c⁸*, provided at its central portion with a depressed thimble portion *c⁹*. The compartment *c⁶* is adapted to contain water, as indicated at *z*, and the compartment *c⁷* is adapted to contain the carbide bodies *z'* and 80 serves as the generating-chamber. 85

f indicates a cylindrical or tubular valve-seat casting provided with a valve-seat *f'*, running longitudinally through the same and having radial perforations *f²* opening outward from said valve-seat *f'*. This valve-casting *f* is secured in working position to the bottom of the depending thimble portion *c⁹* of the partition *c⁸* in an axial position concentric to the center of the passage *c³* in the 95 upper cylinder-head *c'*.

f³ indicates a needle-valve the stem of

which has screw-threaded engagement f^4 with the upper portion of the valve-seat casting f , and the lower end of which terminates in a long needle-point f^5 , which is adapted to open and close the passage in said valve-casting f , and depends a considerable distance below said casting, so as to serve as a dripping-point for the water which is fed into the generator-compartment c^7 . The upper end of this valve f^3 is provided with an annular or open head f^6 , which works through the passage c^8 and affords ready means for adjusting said valve. The opening through the center of this head f^6 is adapted to be nearly closed by means of a removable screw-threaded plug f^7 , provided with a small air-passage f^8 . The passage f^8 is sufficiently large to permit atmospheric pressure to be always effective on the water z in the compartment c^6 , but will prevent the said water from being thrown outward therethrough under the vibrating action incident to its use on a bicycle.

g indicates a small cylindrical holder, formed of perforate material, adapted to telescope at its open upper end over the depending thimble portion c^9 and to contain a small sponge or similar absorbent material, (indicated at y .) The said holder g is of a size which will pass readily through the opening in the nipple c^4 of the lower cylinder-head c^2 , and, as shown, is held upward in its working position by means of a small stem or rod g' , depending from the bottom of said holder and resting on the interior of the cap-nut c^5 . The important function performed by the sponge y or similar absorbent material will be fully set forth in the description of the action or operation of the lamp.

The gas which is generated in the generating-chamber c^7 is conveyed first through a condensing-coil k , wound in the water-compartment c^6 , with its lower end opening through the dividing-partitions c^8 and its upper end projecting outward through the cylindrical casing c and terminating in a coupling end or nipple k' . This coupling end or nipple k' is connected with the receiving end of the burner b' of the bull's-eye b by means of a small hose or flexible gas-conveying connection k^2 , provided with the stop-cock k^3 , by means of which the flow of gas therethrough may be stopped.

In order to keep the pressure of the gas generated and contained in the generating-chamber c^7 practically constant regardless of slight variations in the speed at which the gas is generated relative to the speed at which it is used, I provide a novel equalizer or compensating device which is formed with an elastic portion adapted to expand and contract under slight variations in pressure, as will be hereinafter described in detail. The preferred form of my pressure-compensating device is illustrated in Figs. 1, 3, and 4, in which construction p indicates a rubber bag or bulb the neck of which is removably secured, but with an air-tight joint, to an outwardly-ex-

tended nipple or extension p' from the condensing-coil k . Preferably this elastic compensating or equalizing bulb p is protected by and incased in a light shield p^2 , removably secured to the side of the cylinder c by means of small screws p^3 or otherwise and provided with a multiplicity of openings or air-passages p^4 .

In the modification illustrated in Fig. 6 a rubber diaphragm p^5 is clamped with an air-tight joint against the side of the cylinder c , surrounding the opening or nipple p' of the condensing-coil k , by means of the shield p^2 8, and screws p^3 .

Directing attention again to the generating-chamber c^7 , it will be noted that I have placed a perforated annular guard-plate c^{10} therein a small distance below the partition c^8 and surrounding the depending thimble portion c^9 . This guard-plate c^{10} , while it readily permits the passage of the gas to the receiving end of the condensing-coil k , serves to hold both the carbid and the products of decomposition from being thrown against or lodging in said receiving end of the coil when the generator is turned upside down in the act of recharging the chamber c^7 with carbid, an action presently to be described.

The generator is held in working position by means of a clamp, as shown, comprising a pair of segmental clamping-sections t , pivoted to the cylinder c at one of their ends and securable together at their outer ends by means of a thumb-screw t' . By means of this clamp the generator may be secured to the steering-head, as shown in Fig. 1, or to the vertical frame-rod or seat-post socket, as shown in Fig. 2.

The water-containing compartment c^6 may of course be readily refilled at any time simply by removing the plug f^7 from the valve-head f^6 . To recharge the generating-chamber c^7 with carbid, it is, however, necessary to remove the generator from the bicycle, and after having removed the lime products, which may be readily done when the cap-nut c^5 is removed, the generator should be turned upside down, in which position said chamber c^7 may be readily refilled with carbid, the cap-nut c^5 replaced in working position, and the generator rendered again ready for use.

The operation of the lamp above described when charged with water and carbid, as above set forth, will be substantially as follows: By adjusting the valve f^3 f^5 the flow of the water from the chamber c^6 into the generating-chamber c^7 may be regulated to give approximately the proper speed of generation. The water which is thus allowed to flow will be dropped from the needle-point f^5 of the needle-valve onto the sponge y in the holder g . When this sponge becomes moistened, the water from the same will of course rapidly evaporate into the air-space in the generating-chamber c^7 . The affinity or attraction between water and carbid is so intense that the carbid bodies in the generat-

ing-chamber will take up the moisture evaporated from the sponge almost as fast as it is evaporated, thus constantly drying the air or gas in said generating-chamber, and consequently hastening the evaporation of water from the sponge. It will thus be seen that the particles of water which are dropped onto the sponge are by the action of evaporation brought into contact with the carbid in infinitely small particles, or, in other words, in the form of a mist or vapor. By this manner of generating the gas without any direct contact between the carbid and the water while in a liquid form the generating action is rendered entirely free from impulses, such as are produced, for example, by dropping the water onto the carbid. By the atomizing action of the sponge the generating action is rendered so nearly perfect and unvarying that for many purposes a yielding pressure equalizing or compensating device may be entirely dispensed with. However, when the device is used as a bicycle-lamp it will be subjected to such severe shaking that in case the sponge is heavily saturated a sudden jar may cause the precipitation of a few drops of water onto the carbid, and this would of course cause slight impulses in the speed of generation of the gas. Under this latter-noted action my improved pressure equalizing or compensating device—that is, the rubber bulb p or diaphragm p^5 , as the case may be—will yield or expand so as to prevent any perceptible variation in the pressure of the confined gas under the slight impulses in the generating action. It is, however, very important to note that I have provided, in connection with the absorbent or porous material which is used to convert the water into almost imperceptibly small particles before it reaches the carbid, means for supplying a graduated quantity of water to said absorbent or porous material, which graduated water-feeding device when properly regulated will prevent said material from becoming oversaturated or loaded with more water than it can hold in suspension. While I have shown a hand-set valve for controlling the water-feed, I do not limit myself to this particular construction. This elastic pressure-equalizing device, while an extremely valuable adjunct to a generator in which the evaporating sponge or absorbent material is employed, is of even more importance when used in connection with a generator in which the water is brought into contact with the carbid intermittently in small quantities or drop by drop. Again, in a generator wherein the said sponge is dispensed with the needle-valve construction illustrated will also serve a more important function—to wit, that the depending point f^6 thereof, which projects below the valve-seat, will serve to cause the water to drop onto the carbid in extremely small or subdivided drops. This while in no sense the equivalent of the atomizing-sponge, will reduce the impulses in the generating

action as much as can possibly be done without vaporizing the water.

It will be remembered that the water-containing compartment c^6 is open to the atmosphere through the perforation f^8 in the screw-plug f^7 . Hence the maximum pressure that can possibly be produced on the gas in the generating-chamber is that pressure which is incident to the pressure of the column of water z . It therefore follows, since there is always a passage open through the valve-casting f during the generating action, that whenever from any unusual cause the pressure of the gas in the generating-chamber is raised above the maximum pressure fixed by the column of water the gas will find an escape first through the valve-seat f' and perforations f^2 into the chamber c^6 , and then through the passage f^8 to the atmosphere. Such an over-generation of gas might of course be caused by the careless setting of the needle-valve, so as to give a much too rapid flow of the water into the generating-chamber. Again, if the construction of the generator be modified so that the escape of the gas in the manner just described cannot take place the equalizing air-bulb p or diaphragm p^5 would upon being expanded beyond its elastic strength be bursted or exploded. This bursting or explosion of the elastic equalizer would of course take place long before the bursting strength of any other part of the apparatus was reached or approached and therefore serves as a safety device. The said elastic equalizing devices are of very small cost and are easily replaced.

It is thought to be obvious from the foregoing description that the several novel devices above disclosed, while they all coöperate when combined in a single generator, may nevertheless be employed in other combinations in some cases with more and in other cases with less efficiency than in the combination specifically illustrated. It is also thought to be equally evident that not only may the said several novel devices be employed in different combinations, but that the features of construction of these devices may themselves be varied within the broad ideas or principles involved in the said devices, all without departing from the spirit of my invention.

Recalling attention to the depending thimble portion c^9 of the partition c^8 it will be noted that this thimble portion increases the altitude of the column of water z in the chamber c^6 and renders it possible to use the water for generating purposes until the same has been lowered nearly or quite to the level of the partition c^8 .

It is also desirable to here call attention to the fact that the statement made broadly in the specification and in certain of the claims to the effect that the water-containing compartment is located above the generating-chamber or carbid-containing compartment does not necessarily imply that the said chambers are located in vertical line directly one over the other, but rather that the said cham-

bers are located at such relative altitudes that the water from the water-containing compartment will under the action of gravity run into the said generating-chamber.

5. What I claim, and desire to secure by Letters Patent of the United States, is as follows:

1. In an apparatus for generating gas from solid and liquid substances, such as carbid and water, the combination with a chamber, 10 for the solid, of a body of absorbent or porous material within said chamber, for distributing the liquid to the solid, and means for supplying a graduated quantity of the liquid to said absorbent or porous material, within the 15 limit of saturation thereof, substantially as described.

2. An apparatus for generating acetylene gas, having in combination, a chamber adapted to contain carbid and provided with a water-inlet, means for supplying water to said inlet, and a body of porous material disposed across the water-inlet and extending approximately over the inlet side of said chamber, substantially as described.

25 3. In a generator, the combination with the generating and water-containing compartments, located respectively, one below the other and in communication through a valved passage, of a removable perforate holder located in the generating-chamber immediately below said valved passage, and a sponge or body of absorbent material located in said perforate holder, substantially as described.

4. In a generator, the combination with the 35 generating and water-containing compartments, of a needle-valve seat opening communication between said compartments, a needle-valve in said valve-seat, a removable cap in the lower end of the generating-chamber, a perforate holder in said generating-chamber, located below said needle-valve and held in place by said removable cap, and a sponge or similar absorbent material held in said perforate holder, substantially as described.

45 5. In an apparatus for generating gas from a solid and a liquid substance, such as carbid and water, the combination with a chamber for the solid, a water-inlet passage opening 50 into the upper portion of said chamber, and means for supplying water to said inlet, of a body of absorbent or porous material within said chamber, located in position to receive the water discharged from said inlet, and to 55 distribute the same to the carbid, substantially as described.

6. The combination with a generating-chamber adapted to contain a solid gas-producer, such as carbid, of a liquid-containing 60 chamber having an opening above its liquid-level, which chambers are in communication with each other through a feed-passage that permits a flow in either direction, and are in such vertical relation that the water will be 65 gravity-fed into said generating-chamber and said feed-passage will serve as an escape-pas-

sage to deliver overgenerations of gas through the liquid of said liquid-containing chamber, substantially as described.

7. The combination with the generating 70 and water-containing compartments located respectively, one below the other and separated by a horizontal dividing-partition with depending thimble portion, of a valve-seat opening through the bottom of said thimble 75 portion, a removable cap in the bottom of said generating-compartment, a perforate holder insertible through the bottom of said generating-chamber, adapted to telescope at its upper end with said depending thimble 80 portion and provided with a supporting-finger depending from its bottom and engageable with the inner face of said removable cap, substantially as described.

8. In a generator, the combination with the 85 generating and water-containing compartments, located respectively, one below the other, and separated by a horizontal dividing-partition, of a needle-valve seat opening through said dividing-partition, and a needle-valve working in said valve-seat and provided with a depending conical or needle point which projects below said valve-seat and serves as a dripping-point for the feed-water, substantially as described.

9. In a bicycle-lamp, the combination with the generator involving the chambers c^6 and c^7 separated by the partition c^8 with depending thimble c^9 , the needle-valve seat f' in the casting f , the needle-valve $f^3 f^5 f^6$ working 100 in said valve-seat, the perforated holder g containing the sponge y , the pipe-section k' opening through the partition c^8 , the rubber bulb p in communication with the generating-chamber c^7 , the perforated shield $p^2 p^4$ incasing 105 said bulb c , and the removable cap c^5 in the bottom of said chamber c^7 , of the bull's-eye b provided with the burner b' which is connected with the said pipe-section k by means of the hose or pipe k^2 , substantially as 110 described.

10. A gas-generator comprising in combination, a generating-chamber, a liquid-chamber above the generating-chamber and a water-passage connecting said chamber packed 115 with porous material extending from the liquid-chamber to the generating-chamber.

11. In a gas-generator, the combination of a generating-chamber, a liquid-chamber above the generating-chamber, an outlet for the liquid to pass from its chamber into the generating-chamber, and a cylindrical or tubular holder for a porous packing through which the liquid percolates, said cylinder or tube 120 extending from the liquid-outlet into the generating-chamber, and said packing extending throughout the length of the same.

12. In a generator for acetylene gas, the combination of a carbid-receptacle, a liquid-chamber above the receptacle, a pipe or tube 130 extending from the liquid-chamber into the carbid-receptacle, through which pipe or tube

the water passes, and a packing of porous material contained within said pipe or tube and extending from the water-inlet to the outlet of the same, said packing being adapted to retard the passage of the liquid.

13. In a generator for acetylene gas, the combination of a carbid-receptacle, a liquid-chamber above the same, a pipe or tube extending from the liquid-chamber into the carbid-receptacle through which pipe or tube the liquid passes, a valve between said pipe or tube and the liquid-chamber, and a packing of porous material contained within the pipe or tube and extending from said valve to the

liquid-outlet from the pipe or tube, said packing acting to retard the passage of the liquid.

14. A gas-generator comprising in combination, a generating-chamber, a liquid-chamber above the generating-chamber, and a tube connecting said chambers packed with porous material extending from the liquid-chamber to the generating-chamber.

In testimony whereof I affix my signature in presence of two witnesses.
